DEEP WELL PUMP

Harold S. Crooks and George Highfield, Tulsa,
Okla., assignors of one-half to Dunn & Lewis,
a partnership composed of Irwin L. Dunn and
James O. Lewis, Tulsa, Okla.

Application May 24, 1935, Serial No. 23,203

13 Claims. (Cl. 103—225)

This invention relates to pumps, and particularly to those of the character employed in lifting fluids from oil and other wells wherein pumping conditions are severe due to the cutting and abrasive action on the working parts and packing elements of the pump incidental to the sand or other abrasive material contained in the well fluid. Mineralized water, which often accompanies oil, also tends to corrode the metal parts of the pump and stiffen the packing so that it is rendered less effective and cannot operate at its full capacity. These effects result in a churning action which in the presence of water causes emulsions that are expensive to separate. To alleviate these difficulties to some extent the packing material is pressed with such force that the friction of the packing against the working barrel will not let the travelling valve or the piston drop readily on the down stroke with the result that the length of stroke and pumping rate is materially decreased.

It is, therefore, the principal object of the present invention to provide a pump and pump packing constructed to overcome these difficulties in order that the pump can be operated efficiently and under full capacity over long periods of time.

In accomplishing this and other objects of the invention, as hereinafter pointed out, we have provided improved details of structure, the preferred forms of which are illustrated in the accompanying drawing, wherein:

Fig. 1 is a vertical sectional view of the lower portion of a well equipped with a pump and pump packing construction embodying the features of the present invention.

Fig. 2 is an enlarged fragmentary section through the working barrel and traveling valve to better illustrate the packing construction whereby a more effective seal is established between the traveling valve and the wall of the barrel.

Fig. 3 is a similar view illustrating the release of pressure of the packing against the wall of the working barrel during the downstroke of the traveling valve.

Fig. 4 is a detail perspective view of one of the packing rings.

Fig. 5 is a vertical section similar to Fig. 2 showing an alternate form of packing construction.

Fig. 6 is a perspective view of one of the retainer rings employed in the construction shown in Fig. 5.

Referring more in detail to the drawing:

1 designates the bore hole of an oil or similar well equipped with a pump 2 embodying the features of the present invention and which is adapted for elevating the oil which collects within the bore hole to the top of the well through 5 a string of tubing 3 as in conventional practice.

The pump 2 includes a cylinder or working barrel 4 having its upper end 5 threadedly connected with the lower end of the tubing 3 by 10 means of a coupling 6, and its lower end 7 connected with a depending strainer section 8 by means of a special coupling 9. The lower end of the strainer section 8, being supported on the bottom of the well, retains the working barrel 15 at a desired elevation for admittance of the oil into the barrel incidental to flow effected by a natural formation pressure of the oil producing sand.

Mounted in the coupling 9, as in conventional 20 practice, is a standing valve 11 having a seat 12 encircling a port 13 therein through which the well fluid is drawn into the interior of the working barrel responsive to the upstroke of a traveling valve 14, later described. Upon the downstroke of the traveling valve the well fluid is 25 trapped within the working barrel by a ball valve 15 which engages the seat 12 and operates within a cage portion 16 of the standing valve.

The traveling valve 14 includes a piston 17 30 comprising a lower guide member 18 of suitable diameter to effect an easy fit within the working barrel, and which has its upper portion 19 turned to a smaller diameter to provide a V-shaped annular recessed shoulder 20 to accommodate the packing elements 21 that are sleeved over the reduced portion of the piston, as best illustrated in Fig. 2. The upper end 22 of the reduced portion 19 is externally threaded as at 35 23 to threadedly connect with an upper guide member 24.

The upper guide member 24 conforms in diameter to the lower member 18 and has an internally threaded socket 25 at its lower end to engage the reduced portion 19. The opposite end 45 of the member 24 terminates in a reduced externally threaded neck 26 which forms an annular shoulder 27 to seat a cage 28 that retains a ball valve 29. Extending axially through the guide members of the piston is a channel 31 through 50 which well fluid is transferred upon down-stroke of the piston to be trapped above the piston on its upstroke incidental to seating of the ball valve 29. The ball valve 29 seats upon a ring insert 32 that has a shouldered portion 33 inset into a 55

- counter-bore 34 at the upper end of the guide member 24, and has an upwardly extending collar portion 35 provided with an annular seat 36 for the ball valve 29. The valve cage 28 terminates in an externally threaded pin 37 for engaging the internally threaded box 38 on the lowermost section of a string of sucker rods 39, whereby the traveling valve is reciprocated within the working barrel, as in conventional practice.
- 10 With the construction thus far described, it will be noted that when the traveling valve is lifted by the rods, upon the up-stroke of the pump, the suction created in the lower end of the working barrel will draw the well fluid through the standing valve, and on the down-stroke the standing valve will seat to cause the entrapped oil to flow through the channel 31 into the upper end of the barrel, so that on the up-stroke seating of the ball 29 will cause the working valve to lift the column of oil in the tubing while an additional supply is drawn into the lower end of the barrel so that upon each succeeding up-stroke of the pump a quantity of oil is displaced from the top of the well.
- 15 25 It will be noted that the packing elements prevent flow of well fluid back between the traveling valves and the walls of the working barrel and it is upon the effectiveness of this packing that the success of the pump depends.
- 30 35 It is, therefore, necessary that the packings seal tightly with the wall of the working barrel upon the upstroke of the pump, but upon the down-stroke the packing should contract to allow free downward movement of the traveling valve.
- 35 In carrying out this feature the packing elements 21 include rings 40 constructed of flexible resilient material, shaped to provide spaced concentrically arranged, upwardly extending lips 41 and 42 to respectively engage the inner surface of the working barrel and the exterior surface of the reduced portion 19 of the piston. The lips 41 are provided with downwardly converging beveled edges 43 and 44, and their lower portions are connected by a web portion 45 having similarly beveled lower faces 46 and 47 to interengage with the beveled edges 43 and 44 of a next lower ring, as shown in Fig. 2, while the faces 46 and 47 of the lowest ring engage the faces of the recessed shoulder 20. The rings are thus mounted in nested relation, so that as the traveling valve moves on the upstroke, the pressure of the fluid acting upon the upper ring presses the lips into respective sealing engagement with the surface of the working barrel and the tubular extension 19 of the piston to prevent backward passage of the fluid.
- 40 45 On the down-stroke of the traveling valve, the pressure acting on the underside faces 46 and 47 of the rings causes the lips to contract from the surfaces to be sealed, as shown in Fig. 3, to allow the traveling valve to move readily and freely within the working barrel and also to allow any sand that may be on the walls of the working barrel to pass without abrading either the working surfaces or the packing.
- 50 55 In order to employ this principle effectively the packing ring is constructed of a material having sufficient flexibility to allow the lips to expand and contract, but which is stout enough to hold the fluid column above the traveling valve.
- 60 65 In cross-section the rings are substantially V-shaped so that the lips normally spread outwardly toward the surfaces they engage and bear in light contact therewith prior to application of the ap-

plied pressures incidental to reciprocation of the traveling valve.

The inner diameter of the rings are preferably of slightly larger diameter than the reduced extension 19 of the piston so that they can turn freely thereon and also have slight vertical movement longitudinally thereof during change of direction of the traveling valve.

In Figs. 5 and 6 the individual packing rings are supported by retainer rings 48 including sleeve portions having inner diameters of sufficient size to fit around the reduced extension 19 of the piston and of sufficient length so that when the lowermost retainer is seated upon the shoulder 49 the upper retainer has its end engaged against the lower end of the upper guide member as best shown in Fig. 5. The retainers are retained in fixed sealing engagement with the piston to prevent leakage therebetween. To further enhance the seal each retainer ring has a beveled edge 50 to seat within a beveled recess 51 formed on the bottom of the next upper retainer.

Extending circumferentially of each sleeve portion of the retainer rings are lateral flanges 52 having V-shaped annular seats 53 in their upper faces to seat the V-shaped portions of the individual packing rings which are of the same type as described in the preferred form of the invention.

It is thus apparent that in this construction each of the packing rings is supported on the piston independently of the others, so that the lips thereof are independently free to sealingly engage the respective surfaces in a manner similarly to the corresponding lips of the rings in the preferred form of the invention.

In using a pump of the type shown in Figs. 1 to 4, inclusive, the pressure of the well fluid acting upon the lips of the upper sealing element, when the piston is reciprocated in an upward direction, acts against the beveled upper ends thereof to enhance their seal with the respective contact surfaces of the working barrel and to effect a corresponding outward pressure on the lower rings incidental to the interengaging beveled surfaces. Upon the down-stroke the pressure acting on the V-shaped lower side of the lower ring causes the outer lips 43 to contract toward the inner lips and release the seal to permit free downward movement of the piston.

Should any sand have collected upon the surface of the wall of the working barrel, it will pass between the lips of the rings without causing an abrading action upon the surfaces of the working barrel or on the sealing surfaces of the packing rings. During reciprocation of the traveling valve the packing rings are free to move up and down and around the piston member so as to increase their flexibility and their adjustability to irregularities in the wall of the working barrel. On the down-stroke the release of the sealing contact reduces wear on the working barrel and packing. Because of the alternate expansion and contraction of the packing rings they better adjust themselves to surface irregularities of the working barrel. The flexibility of the rings helps to maintain the seal of the rings on the upstroke for the reason that when one ring is flexing over a surface irregularity one or more of the other rings are in contact with smooth surfaces of the barrel to maintain the seal. The flexible lips also wipe off sand on the up-stroke rather than to grind it against the working surfaces, while they permit the sand to

pass between the packing rings and the working barrel on the down-stroke.

The packing rings in the form of invention shown in Figs. 5 and 6 operate substantially in the same manner, but depend upon the direct action of the fluid rather than the wedging action of the nested packing rings.

From the foregoing it is apparent that we have provided a pump and packing construction which is more efficient in operation and can be kept operating at its maximum capacity over long periods of time, since we have reduced the wear and increased the effective life of the packing elements.

15 While we have described the packing rings in association with a definite type of pump, it is obvious that they can be employed in other types of pumps, such as the plunger and liner types, without departing from the spirit of the invention.

20 What we claim and desire to secure by Letters Patent is:

1. In a pump including a working barrel, a traveling member reciprocable within the working barrel, a packing ring loosely supported on the traveling member and slideable relative thereto, said packing ring having spaced lips respectively engaging the traveling member and said working barrel to seal the space therebetween responsive to stroke of the traveling member in one direction and to release said sealing engagement upon movement of the traveling member in the opposite direction.

2. In a pump including a working barrel, a traveling member reciprocable within the working barrel, a plurality of nested V-shaped packing rings mounted on said member and having lips respectively engaging said working barrel and said member to effect a seal with the working barrel upon reciprocation of the traveling member in one direction and contractible from said sealing engagement upon reciprocation of the traveling member in the opposite direction.

3. In a pump including a working barrel and a traveling valve reciprocable within the working barrel, the traveling valve having guide portions connected by a reduced cylindrical portion, a plurality of nested V-shaped packing rings reciprocably and loosely mounted on said reduced portion and having lips respectively engaging said working barrel and said reduced portion to effect a seal with the working barrel upon reciprocation of the traveling valve in one direction and contractible from said sealing engagement upon reciprocation of the traveling valve in the opposite direction.

55 4. In a pump including a working barrel, a traveling valve reciprocable within the working barrel and having guide portions connected by a reduced cylindrical portion, a plurality of flexible packing rings having lips respectively engaging said working barrel and said reduced portion to effect a seal with the working barrel upon reciprocation of the traveling valve in one direction and contractible from said sealing engagement upon reciprocation of the traveling valve in the opposite direction, and retainers on said reduced portion for supporting said packing rings.

5. In a pump including a working barrel, a traveling valve reciprocable within the working barrel and having guide portions connected by a reduced cylindrical portion, a plurality of V-shaped packing rings reciprocably and loosely mounted on said reduced portion and having lips respectively engaging said working barrel and said reduced portion to effect a seal with

the working barrel upon reciprocation of the traveling valve in one direction and contractible from said sealing engagement upon reciprocation of the traveling valve in the opposite direction, and retainers spacing said packing rings.

5 6. In a pump including a working barrel and a traveling valve reciprocable within the working barrel, a plurality of V-shaped packing rings reciprocably and loosely supported on the traveling valve and having spaced lips respectively engaging the traveling valve and said working barrel to seal the space therebetween responsive to stroke of the traveling valve in one direction and to release said sealing engagement upon movement of the traveling valve in the opposite direction, said lips having converging beveled edges engaging the V-shaped portions of said packing rings.

10 7. In a pump including a cylinder and a piston slidably engaging the cylinder, and a packing element movably mounted on the piston and slideable relative thereto, said packing element having lips respectively engaging said cylinder and piston responsive to pressure applied to one side of said packing element and releasable from 15 said engagement upon pressure applied to the opposite side of said element.

20 8. In a pump including a cylinder and a piston slidably engaging the cylinder, and a packing element movably mounted on the piston and slideable relative thereto, said packing element having lips respectively engaging said cylinder and piston responsive to pressure applied to one side of said packing element and releasable from 25 said engagement upon pressure applied to the opposite side of said element incidental to reciprocation of the piston.

25 9. In a pump including a cylinder and a piston slidably engaging the cylinder, and a packing element movably mounted on the piston and slideable relative thereto, said packing element being of V-shaped cross-section and having lip portions respectively engaging said cylinder and piston responsive to fluid pressure applied to one 30 side of said element and releasable from said engagement upon pressure applied to the opposite side incidental to reciprocation of the piston.

40 10. In a pump including a cylinder and a piston slidably engaging the cylinder, and a plurality of superimposed packing elements loosely carried by the piston and slideable relative thereto, said packing elements having spaced lips respectively engaging said cylinder and piston, whereby application of pressure 45 to one side of the packing elements effects sealing contact of said lips and whereby pressure applied to the opposite side of the packing elements contracts said lips from said sealing contact.

50 11. In a pump including a cylinder and a piston slidably engaging the cylinder, and a plurality of superimposed packing elements carried by the piston and having V-shaped cross-section to provide spaced lips respectively 55 engaging said cylinder and piston and having V-shaped connecting portions arranged with the V-shaped connecting portion of one element nested between the lips of a lower element whereby application of pressure to one of the elements 60 effects sealing contact with said cylinder and piston and whereby pressure applied to another of the elements contracts said elements from said sealing contact incidental to reciprocation of said piston.

12. In a pump including a cylinder and a piston slidably engaging the cylinder, and a plurality of superimposed packing elements carried by the piston and having V-shaped cross-section to provide beveled lips respectively engaging said cylinder and piston and having V-shaped connecting portions arranged with the V-shaped connecting portion of one element nested between the beveled lips of a lower element, whereby application of pressure to one of the elements effects sealing contact with said cylinder and piston and whereby pressure applied to another of the elements contracts said elements from said sealing contact incidental to reciprocation of said piston.
13. In a pump including a cylinder, a piston

reciprocable within the cylinder and having a reduced extension, a plurality of packing rings reciprocably supported on the reduced extension and having spaced lip portions provided with converging beveled edges, and having V-shaped portions whereby the V-shaped portions of one packing ring engage the beveled lip portions of an adjacent packing ring to cause movement of said lip portions into sealing engagement with said piston and cylinder when the packing rings 10 reciprocate incidental to movement of the piston in one direction and to allow flow of fluid between said lip portions when the piston is moved in the opposite direction.
